COATING MACHINE

Wilbur L. MacKenzie, Beverly, Mass., assignor to
 United Shoe Machinery Corporation, Paterson,
 N. J., a corporation of New Jersey

Application February 25, 1935, Serial No. 8,003

40 Claims. (Cl. 12—17)

This invention relates to machines by which work-pieces are coated, it being particularly concerned with the application of the coating in connection with another operation. An example of work for which this machine is well adapted is the cementing of the breast-flaps of shoe-soles for the purpose of effecting their temporary attachment to the sole-bodies from which they have been divided. Another form of the invention, 10 specific to the present case, is made the subject of an application for Letters Patent of the United States, filed simultaneously herewith and numbered 8,004, the title of which is Coating-applying machine.

It is a common practice in connection with women's shoes to split from the grain-side of a sole a thin flap, which may later be cemented to the breast of a heel attached to the shoe, to furnish a covering for said breast. Between the 20 splitting and breast-covering operations, various other manufacturing steps occur involving the sole. For example, in a cement-process shoe, there are the operations of shank-reducing, roughing of the flesh-side, the application of cement and then a solvent thereto, and the pressing of the sole upon the shoe-bottom. While this is being done, the rather frail, loose breast-flap is obviously liable to injury, as by creasing or tearing. It is an object of my invention to 30 guard against difficulties of this character, and with this in view I have provided a machine which may, among its various uses, be employed to temporarily attach a breast-flap to the opposed surface of its sole, to be separated therefrom when it is to be cemented to the heel-breast. As above 35 indicated, this attachment may be associated with other operations upon the work, as the splitting of the flap from the sole-body. This is not, however, an essential part of the present invention, 40 which, more broadly, is directed to the attachment of the work-portions to one another.

For the attainment of my object, I combine means acting between opposed surfaces, as of a sole-body and a flap divided therefrom, to turn the flap away from the body while it is supported to receive the turning action, and means for applying cement or other coating material to the separated surfaces, in the present instance to the surface of the flap. Thereafter, the work is acted upon by means which brings the work-portions together and applies pressure to them. The flap is thus held against mutilation, adhering to the sole-body until its separation for operations upon it is desired. To facilitate this separation, the 55 coating is applied over less than the entire area

of the surface, leaving a portion which may be grasped by the operator for its detachment. The application of the coating may be by such a device as a nozzle, and this I have shown as mounted upon a carriage arranged to reciprocate along a table upon which the work is supported. With the nozzle, or other applying device, upon the carriage, a receptacle for the coating material, a pump for causing the delivery of said material, and a pressure member for the work may be 10 mounted. A movement of the nozzle to bring it into and out of applying relation, together with movement of the pressure member and actuation of the pump, are preferably caused or controlled, either by the reciprocation of the carriage or by 15 a raising and lowering of the table. The attaching operation is most effectively carried out in connection with another operation upon the work, an efficient procedure being to combine the attachment with the division or splitting of the 20 flap from the sole-body. For this purpose, a splitting knife is best mounted upon the carriage, this knife producing its cut during relative movement between said carriage and the work in one direction and while the work-supporting table is 25 in its elevated position. As the knife divides the flap, it turns it back from the sole-body, giving the nozzle or other applying device access to the just severed surface to effect its coating. An abutment upon the carriage, along which the 30 flap is thus turned, holds said flap for the action of the nozzle upon it. During relative movement between the operating elements and work in another direction, as, for example, one opposite to the direction of movement during the 35 making of the cut, the opposed surfaces of the flap and sole-body are brought together and pressure applied thereto.

A single embodiment of my invention is illustrated in the accompanying drawings, in which

Fig. 1 is a broken side elevation of the improved machine with the elements in their normal positions;

Fig. 2, a similar view with the carriage at the forward extreme of its travel and just after the table has dropped;

Fig. 3, an end elevation looking from the right in Fig. 1;

Fig. 4, a horizontal section through the valve mechanism of the pump;

Fig. 5, an enlarged longitudinal sectional detail showing the nozzle in its applying position; and

Fig. 6, a similar view with the elements as related during the application of pressure to the work.

In Letters Patent of the United States No. 1,224,918, Furber, May 8, 1917, is disclosed a machine to which my invention may advantageously be applied. The more essential elements of the apparatus of the patent and the manner in which they co-operate are as follows: Upon a base 10 is mounted an actuating member 12 (Fig. 3), from the opposite sides of which project rolls 14. These rolls lie within inclined slots 16 in the sides 5 of a work-supporting table 18. By a spring 20 (Fig. 2), interposed between a portion of a base and a lug depending from table, said table is urged normally to the left as viewed in Figs. 1 and 2 of the drawings, the interaction of the rolls 10 and slots causing it to occupy at this time its lowest position. Movable upon ways 22 extending longitudinally at opposite sides of the table is a carriage 24, and fixed transversely upon it are a splitting knife 26 and a gage 28 (Fig. 5) 15 which is a mutilated cylinder adjustable about its axis to determine the depth of cut of the knife. A rotatable operating member 30 is joined by a link 32 to the carriage 24 to reciprocate this over the table, and bears a cam 34, which, by 20 engagement with a roll 36 upon the table 18, moves said table longitudinally sufficiently to raise and lower the table 18 on the rolls 14 transversely of the path of reciprocation of the carriage. At the beginning of an operating cycle a 25 sole S to be split at the heel-portion to furnish a breast-flap s is laid upon the table, and the machine started in operation. The cam 34 shifts the table to the right (Fig. 1) over the rolls 14 to raise it to splitting position, and the link 32 30 moves the carriage 24 to the right to cause the knife 26 to divide the breast-flap from the body of the sole. The cut having been completed, the cam frees the table, which travels to the left under the influence of the spring 20. This lowers 35 the table to relieve the work of the pressure of the gage, while the link restores the carriage to its initial position, the splitting operation having been thus completed.

To coat one of the divided surfaces with an 40 adhesive and thus prepare for the attachment of the two surfaces to each other by pressure over the coated area, there is mounted upon one of a pair of standards 40, 40, rising from opposite sides of the carriage 24, a cement-receptacle 42. 45 Fulcrumed upon a bracket 43 depending from a bar 44 joining the standards is a bell-crank-lever 46, which, at its lower extremity, has secured to it a nozzle 48. The outlet-portion 50 of this nozzle is shown as curved forwardly toward the 50 gage 28. It acts upon the work against the resistance to displacement offered by a curved abutment-plate 52, depending from a cross piece 53 forming part of the carriage at the forward side of the gage. A spring 51 joining the bell 55 crank 46 and hence the nozzle to one of the standards 40 exerts its force to draw said nozzle normally toward the plate. A flexible pipe 54 connects the nozzle to a pump-cylinder 56 mounted at the lower portion of the carriage at one side 60 of the base 10. A piston 58 operates in the cylinder, relative movement between the two being produced by contact of collars 60 and 62 upon the piston-rod 64 with normally stationary elements upon the base. This action will later be explained. A pipe 66 delivers cement from the receptacle 42 to the pump-cylinder through a spring 68, as illustrated in Fig. 4, when relative movement of the cylinder and piston produces suction. Upon relative movement in the 70 opposite direction, the drawn-in charge is forced 75

through a spring check-valve 68 and thence, via the pipe 54, out of the nozzle. A check-valve 71, interposed between the pipes 54 and 66 in a bypass 73, allows the quantity of cement supplied to the nozzle to be regulated, a spring 75, which seats the valve, being adjustable as to its resistance by a screw 77.

It is desired that during the forward or cutting travel of the carriage 24, the nozzle 50 shall be held away from the plate 52, to give a space to 10 receive the split-off flap s while the charge of cement is being drawn from the receptacle 42 into the pump-cylinder 56. During the rearward or reverse travel, the nozzle is to be moved in against the flap, which has been raised from the body of 15 the sole above the knife and into proximity to the plate 52, and the cement is forced by the pump through the nozzle upon the inner face of the flap. Further, the cemented flap is to be pressed down upon the sole-body to effect its 20 adhesion thereto. These operations are accomplished in the following manner:

The upper arm of the lever 46 is united by a link 70 to a lever 72 fulcrumed at 73 on the carriage 24. This lever carries two rolls, one, 74, 25 turning about the pivotal connection of the link, and the other, 76, rotatable on a stud secured to the lever between its extremities. As best shown in Fig. 1, in the initial position of the carriage 24 the roll 76 rests upon the upper edge of 30 a cam-plate 78. This plate is adjustable along the path of the carriage by slot-and-screw connections 79 to vary the time of its effect. The contact with the cam-plate so turns the lever 72 clockwise that the link 70 correspondingly rotates the lever 46, to hold the nozzle separated from the plate 52 against the force of the spring 51. As the carriage advances in its forward cutting travel, the roll 76 reaches a downward incline 80 at the end of the cam-plate 78. Now, 40 however, since the table 18 has been raised into its cutting position by the rolls 14 and slots 16, an edge of said table contacts with the roll 74 on the lever 72, so the inactive relation of the nozzle is maintained. This continues until that 45 operating period illustrated in Fig. 2 is attained and after the splitting-off of the flap s has been completed. Now the table is lowered and the travel of the carriage is reversed. As the table-edge leaves the roll 74, the spring 51 carries the 50 nozzle into engagement with the flap, which is backed by the plate 52. The bodily movement of the nozzle with the carriage applies a strip of cement along the center of the flap from near its juncture to the sole-body to a point somewhat 55 removed from the free end, which end is to be left uncoated. At this time the roll 76 strikes and rides up the cam-incline 80, causing the lever-and-link-connections to swing the nozzle to its inactive position. The elements finally assume the relation illustrated in Fig. 1.

As to the supply of cement from the receptacle 42 to the nozzle 50, inspection of Fig. 1 will show that the operating cycle starts with the piston 58 in its final discharging position. As the carriage 65 24 travels to the right, the cylinder 56 and the piston first move together, their relation to each other not changing. The piston-rod 64 passes through a perforated stop-lug 82 upon the base. When, at an intermediate point in the advance of 70 the cylinder and piston, the collar 60 strikes the lug, it is retained thereby and the piston remains at rest while the travel of the cylinder continues. This applies suction to the valve 68, opening it and drawing into the cylinder a charge of cement 75

through the pipe 66, as appears in Fig. 2. During the taking in of the charge, the valves 69 and 71 are held seated. At the completion of splitting travel of the carriage 24, the collar 62 has just passed a detent 84 pivoted upon the cam-plate 78 and urged into the path of the collar by a spring 86. The detent retains the piston-rod and piston against rearward movement, while the travel of the cylinder continues. This forces the cement out of the cylinder through the now opened valve 69, the valve 68 being closed by the pressure. Delivery of the cement to the flap through the nozzle in its active position occurs, the amount being controlled by adjustment of the spring 75 of the valve 71, which may be caused to divert a greater or less quantity through the bypass 73. At the time the nozzle is removed from the flap by the engagement of the roll 76 with the cam-incline 80, said roll strikes the detent, which it overlaps, and lifts it from the collar 62. The piston now being free to travel with the cylinder, the discharge from the nozzle 50 ceases because there is no longer a force acting to expel the adhesive from the cylinder. The collar 62 moves past the detent, which is restored by the spring 86 to its normal position. The quantity of cement taken into the cylinder and the beginning and end of its expulsion may be altered by adjustment of the cam-plate 78 and the collars 60 and 62.

30 A portion of the length of the flap *s* having been thus coated, it is to be pressed against the body of the sole *S* to cause its adhesion. Shown as pivoted to turn about the same axis as the gage 28, and extending forwardly from the carriage 24 along the table 18, are arms 90 in the free extremities of which is fixed a pressure-rod 92. Between the rod and its pivot-point, each arm has mounted to rotate upon it a roll 94 arranged for contact with a table-edge, against which it is drawn by a spring 96 uniting the arm to the base. Noting that the rod is farther removed from the pivotal axis than the rolls, and that the rod is consequently movable through a more extended arc, the relation of the peripheries of the rod and rolls is such that with the table raised during the cutting stroke of the splitting knife 26, engagement of said table with the rolls so positions the rod that it exerts no pressure upon the work. When, however, the table drops for the return travel, the rod is lowered into engagement with the work (Fig. 6) and is dragged over it toward the flap *s*. This forces the coated under surface against the opposite sole-surface to effect adhesion.

To briefly outline the operation of the apparatus, and assuming that a breast-flap *s* is to be split from a sole *S*, with the elements located as appears in Fig. 1 of the drawings, the operator places the sole longitudinally of the table 18 with the heel-end pointing inwardly and applies power to rotate the operating member 30. The cam 34 and the cooperating rolls 14 and slots 16 raise the table, and the link 32 moves the carriage 24 over the sole, so a flap of a thickness determined by the setting of the gage 28 is split and left attached to the sole at its base. As this occurs, the flap is turned up over the inclined upper bevel of the knife between the abutment-plate 52 and the nozzle 50. Said nozzle is held spaced from the plate by the successive action of the cam-plate 78 and the margin of the table upon the rolls 76 and 14, respectively. The rod 92 is held clear of the work by the rolls 94 resting upon the elevator table. A charge of cement is drawn into the cylinder 56 from the receptacle 42 under the control of the collar 60. The flap-cutting having been

completed, the table is lowered, and, as it leaves the roll 74, the spring 51 urges the nozzle 50 downwardly against the flap near its base, forcing it against the plate 52. As the table falls, the rod 92 is drawn down upon the sole by the spring 96. 5 During the travel of the carriage 24 rearwardly, the knife is carried from beneath the flap, the piston 58 is retained by the collar 62 and the detent 84 and delivers cement from the cylinder through the nozzle upon the inner face of the 10 flap, as appears in Fig. 5. Upon engagement of the roll 76 with the detent 84 and the cam-incline 80, the discharge is stopped and the nozzle is withdrawn from the flap. When the rod 92 reaches the flap, it forces it against the body of the sole. 15 This last-mentioned effect is illustrated in Fig. 6. The carriage is brought at the close of the operating cycle to the normal position of Fig. 1. In the work thus completed a sufficient portion of the flap is so attached to the sole by the adhesive 20 that its injury during subsequent operations will be guarded against, but the free end may readily be grasped by the operator and the remainder of the flap drawn away from the sole when such separation is desired. 25

Having described the invention, what I claim as new and desire to secure by Letters Patent of the United States is:

1. In a machine for attaching to a shoe-sole a flap divided therefrom, means for turning the 30 flap away from the sole-face from which it was divided, a support upon which the sole rests to receive the action of the turning means, means for applying an adhesive coating to one of the surfaces separated by said turning means, and 35 means for bringing the opposed surfaces together and for applying pressure thereto.

2. In a machine for attaching to a shoe-sole a flap divided therefrom, means for turning the flap away from the sole-face from which it was divided, means for applying an adhesive coating to one of the surfaces thus separated, the sole and applying means being movable relatively in different directions with the applying means effective during relative movement in one direction and ineffective during movement in another direction, and means for bringing the opposed coated surfaces together and for applying pressure thereto. 40 45

3. In a machine for temporarily attaching to a shoe-sole a heel-breast-flap split therefrom, means for turning back the flap, means for applying an adhesive coating to one of the separated surfaces over less than its entire area, and means for bringing the coated surface and the opposed surface together and applying pressure thereto to effect partial adhesion. 50 55

4. In a machine for attaching to a shoe-sole a flap divided therefrom, a flap-turning member engaging the flap to separate it from the sole- 60 body, a support upon which the sole rests to receive the action of the turning means, a cement-applying member delivering to one of the separated surfaces of the supported sole, and a member contacting with the flap to bring such separated surfaces together. 65

5. In a machine for cementing the breast-flaps of soles, a support for a sole, means for turning the flap away from the sole-face from which it was divided, means for producing relative movement between the support and turning means to render said turning means effective, and a nozzle for delivering cement between the flap and face. 70

6. In a machine for cementing the breast-flaps of soles, a support for a sole, means for turning 75

- the flap away from the sole-face from which it was divided, a cement-delivering nozzle, and means for moving the nozzle between the flap and face.
5. 7. In a machine for cementing the breast-flaps of soles, a support for a sole, means for turning the flap away from the sole-face from which it was divided, an abutment toward which the flap is turned, and a cement-applying device urging the 10 flap toward the abutment.
8. In a machine for cementing the breast-flaps of soles, a support for a sole, means for turning the flap away from the sole-face from which it was divided, an abutment toward which the flap is turned, a cement-applying device urging the flap toward the abutment, and a member contacting with the flap to press it against the body of the sole.
9. In a machine for cementing the breast-flaps 20 of soles, a movable support for a sole, means for raising and lowering the support, a cement-applying device operating between the body and the flap, means contacting with the cemented flap to press it against the sole-body, and means controlled by the raising and lowering of the support for varying the relation of the pressing means to the sole.
10. The combination with mechanism for cutting an integral piece of material, thereby forming new faces, of means for applying an adhesive to a face formed by the cutting, and means for pressing the newly formed faces together.
11. The combination with a support for material, of means for dividing the material, means for 35 producing relative movement in opposite directions between the support and dividing means, said dividing means being made effective during the relative movement in one direction, and means for applying an adhesive to the divided material during the relative movement in the opposite direction.
12. The combination with a support for material, of means for dividing the material, means for producing relative movement in opposite 45 directions between the support and dividing means, said dividing means being made effective during the relative movement in one direction, means for applying an adhesive to a face formed by the division during the relative movement in the other direction, and means acting during continued relative movement in said other direction for pressing the divided faces together.
13. The combination with a support for a shoe-sole, of a cutter traveling longitudinally of the 55 support and sole, and an adhesive-applying device traveling with the cutter in applying relation to the cut surface.
14. In a machine for forming breast-flaps upon soles, a cutter for producing a flap upon a sole, and an adhesive-applying device acting between the sole and flap.
15. In a machine for forming breast-flaps upon soles, a cutter for producing a flap upon a sole, and an adhesive-applying device movable into 65 and out of the space formed between the sole and flap.
16. In a machine for forming breast-flaps upon soles, a cutter for producing a flap upon a sole, an adhesive-applying device acting between the sole and flap, and a pressure member engaging the flap after the applying device has acted.
17. In a machine for forming breast-flaps upon soles, a cutter for producing a flap upon a sole, an adhesive-applying device acting between the 75 sole and flap, and means for rendering the adhe-
- sive-applying device effective over a portion only of the length of the flap.
18. The combination with a work-supporting table, of a carriage movable along the table, a cement-applying device movable upon the carriage, and stationary means for controlling the position of the applying device to move it into cooperative relation to a piece of work on the table. 5
19. The combination with a sole-supporting table, of a carriage mounted to reciprocate along the table, means upon the carriage for separating portions of the sole, a cement-applying device movable upon the carriage into and out of applying position, and means for moving the applying device into applying position between the 15 separated sole-portions during movement of the carriage.
20. The combination with a movable work-supporting table, of means for raising and lowering the table, a carriage movable along the table, a 20 cement-applying device mounted upon the carriage to operate upon the work, and a pressure member movable upon the carriage and by the table in contact with the work.
21. The combination with a work-supporting table, of a carriage movable along the table, a cement-receptacle mounted upon the carriage, a 25 nozzle receiving cement from the receptacle and being movable by the carriage over the work and movable upon said carriage, and means effective 30 during the return movement of the carriage for moving the nozzle thereon into coating relation to the work.
22. The combination with a work-supporting table, of a carriage movable along the table, a cement-receptacle and a pump mounted upon the carriage, a nozzle movable upon and with the carriage and through which the pump applies cement from the receptacle to a piece of work on the table, and means for actuating the pump and 40 moving the nozzle upon the carriage.
23. The combination with a work-supporting table, of a carriage movable along the table, a cement-receptacle mounted upon the carriage, a 45 nozzle receiving cement from the receptacle and being movable upon the carriage and by the advance thereof over the work, a lever fulcrumed upon the carriage and connected to the nozzle, and a cam receiving contact of the lever to move the nozzle. 50
24. The combination of a movable work-supporting table, of means for raising and lowering the table, a carriage movable along the table, a cement-applying device movable upon the carriage, and means acted upon by the table for moving the cement-applying device upon the carriage into and out of applying relation. 55
25. The combination of a movable work-supporting table, of means for raising and lowering the table, a carriage movable along the table, a cement-receptacle mounted upon the carriage, a nozzle movable upon the carriage and receiving cement from the receptacle, and a lever fulcrumed upon the carriage and connected to the 60 nozzle, said lever being movable as a result of the raising and lowering of the table. 65
26. The combination with a work-supporting table, of a carriage reciprocating along the table, a cement-receptacle and a pump mounted upon the carriage, a nozzle through which the pump applies cement from the receptacle to the work, and means including a releasable latch acting during reciprocations of the carriage in opposite directions for causing respectively filling and expelling movements of the pump. 70
- 75

27. The combination with a base, of a carriage movable thereon, a cement-receptacle mounted upon the carriage, a pump-cylinder upon the carriage receiving cement from the receptacle, a 5 piston movable in the cylinder, a nozzle to which the cylinder delivers, and means fixed upon the base for shifting the piston in opposite directions in the cylinder.

28. The combination with a base, of a carriage 10 movable thereon, a cement-receptacle mounted upon the carriage, a pump-cylinder upon the carriage receiving cement from the receptacle, a piston movable in the cylinder, a nozzle to which the cylinder delivers, means carried by the base 15 for arresting the movement of the piston with the cylinder, and means for releasing the piston from the arresting means.

29. The combination with a base, of a carriage movable thereon, a cement-receptacle mounted 20 upon the carriage, a pump-cylinder upon the carriage receiving cement from the receptacle, a piston movable in the cylinder, a nozzle to which the cylinder delivers, means carried by the base for arresting the movement of the piston with 25 the cylinder, and means upon the carriage for releasing the piston from the arresting means.

30. The combination with a base, of a carriage movable thereon, a cement-receptacle mounted upon the carriage, a pump-cylinder upon the carriage receiving cement from the receptacle, a piston movable in the cylinder, a nozzle movable upon the carriage and to which the cylinder delivers, means carried by the base for arresting the movement of the piston with the cylinder, and 35 means upon the base for moving the nozzle and releasing the arresting means.

31. The combination with a base having a stop-portion, of a carriage movable on said base, a cement-receptacle mounted upon the carriage, a pump-cylinder upon the carriage receiving cement from the receptacle, a piston movable in the cylinder, a nozzle movable upon the carriage and to which the cylinder delivers, a movable detent carried by the base and acting upon 45 the piston for arresting the movement of the piston with the cylinder, and a lever fulcrumed upon the carriage and connected to the nozzle to move it, said lever acting upon the detent to release the piston.

50 32. The combination with a base having a stop-portion, of a carriage movable on the base, a cement-receptacle mounted upon the carriage, a pump-cylinder on the carriage receiving cement from the receptacle, a piston movable in the cylinder, a nozzle movable upon the carriage and to which the cylinder delivers, a movable detent carried by the base and acting upon the piston for arresting the movement of the piston with the cylinder, a lever fulcrumed upon the carriage 55 and connected to the nozzle to move it, said lever acting upon the detent to release the piston, and means carried by the base for actuating the lever.

33. The combination with a sole-supporting 65 table, of a carriage movable along the table, a splitting knife mounted upon the carriage and acting upon the sole, and a coating nozzle mount-

ed upon the carriage and delivering between the split piece and the body of the sole.

34. The combination with a work-supporting table, of a carriage movable along the table, a splitting knife mounted upon the carriage and acting upon the work, a coating nozzle movable upon the carriage and delivering to the work, and an abutment toward which the nozzle moves and along which the split material is turned by the knife. 5

35. The combination with a work-supporting table, of a carriage movable along the table, a splitting knife upon the carriage acting upon the work, a coating nozzle upon the carriage delivering to the split work, and a pressure member 15 movable by the carriage over the split and coated work. 10

36. The combination with a work-supporting table, of a carriage reciprocating along the table, a knife mounted upon the carriage to split the 20 work upon movement of the carriage in one direction, and a coating nozzle mounted upon the carriage and delivering to the split work upon movement of said carriage in the opposite direction. 25

37. The combination with a work-supporting table, of a carriage reciprocating along the table, a knife mounted upon the carriage to split the work upon movement of the carriage in one direction, a coating nozzle mounted upon the carriage and delivering to the split work upon movement of said carriage in the opposite direction, and means limiting the discharge from the nozzle upon the work to a portion only of such 30 opposite movement. 35

38. The combination with a work-supporting table, of a carriage reciprocating along the table, a knife mounted upon the carriage to split the work upon movement of the carriage in one direction, a coating nozzle mounted upon the carriage and delivering to the split work upon movement of said carriage in the opposite direction, a pressure member movable by the carriage into effective engagement with the work during its 45 cement-receiving travel, and means for relieving the work of such pressure during the splitting movement of the carriage. 40

39. The combination with a reciprocatory carriage, of a movable work-supporting table along which the carriage travels, means for moving the 50 table transversely of the path of travel, a splitting knife upon the carriage acting upon the work, a cementing nozzle movable upon the carriage and delivering to the work, and means dependent upon both the movements of the table 55 and carriage for moving the nozzle.

40. The combination with a reciprocatory carriage, of a movable work-supporting table along which the carriage travels, means for moving the table transversely of the path of travel, a splitting knife upon the carriage acting upon the work, a cementing nozzle upon the carriage delivering to the work, a pressure member mounted upon the carriage, and means controlled by the movement of the table for rendering the pressure member effective and ineffective. 60 65

WILBUR L. MACKENZIE.
